UNITED STATES PATENT OFFICE.

NICOLAUS AUGUST OTTO, OF COLOGNE, PRUSSIA, ASSIGNOR TO THE GAS MOTOREN FABRIK DEUTZ, OF DEUTZ-ON-THE-RHINE, GERMANY.

APPARATUS FOR HEATING THE IGNITION-TUBES OF GAS-MOTOR ENGINES.

SPECIFICATION forming part of Letters Patent No. 388,301, dated August 21, 1888.

Application filed February 9, 1888. Serial No. 263,478. (No model.) Patented in England December 29, 1887, No. 17,896; in Belgium January 18, 1888, No. 80,305, and in Italy March 31, 1888, No. 22,898.

To all whom it may concern:

Be it known that I, NICOLAUS AUGUST OTTO, a citizen of Prussia, residing at Cologne, in the German Empire, engineer, have invented certain new and useful Apparatus for Heating the Igniting-Tubes of Gas-Motor Engines, (for which I have obtained a patent in Belgium, January 18, 1888, No. 80,305; Italy, March 31, 1888, No. 22,898, and have made application 5 for patent in Great Britain December 29, 1887, No. 17,896,) of which the following is a specification.

This invention relates to apparatus for externally heating the tubes by means of which 15 the combustible charges of motor-engines are ignited; and it has for its object to effect such heating by the combustion of vapor produced by the volatilization of benzine or other volatile combustible liquid. For this purpose a 20 closed receptacle of spherical or other shape charged with combustible liquid is fitted at top with a tube reaching down inside the same to near the bottom, and having an internal screwed thread through which is screwed a screw-rod, 25 the lower end of which acts as a valve for more or less closing a small opening at the bottom of the receptacle, through which the combustible liquid can pass in regulated quantities into a pipe conducting it downward to a 30 point where external heat is applied for volatilizing the liquid as it flows down. The resulting combustible vapor then passes through a continuation of the pipe to a nozzle or Bunsen burner, where it mixes and enters into 35 combustion with the air. For heating the said pipe any convenient source of heat may be used, such as part of the heat produced by the combustion of the vapor itself or the heat radiated from the motor-engine; but by preference the necessary heat is supplied by fixing or forming round the supply-pipe a small 40 annular chamber having at top a number of small jets and communicating by a small hole regulated by a screw-plug with the interior of 45 the pipe, so that a portion of the vapor generated passes into the annular chamber and issues through the jets thereof. In order to produce the requisite quantity of vapor for 50 supplying these jets in the first instance, a cup is fixed on the supply-pipe underneath the an-

nular chamber, for the reception of a small quantity of volatile combustible liquid which is ignited.

The said apparatus may be employed in combination with any form of Bunsen or other 55 burner and igniting-tube, such as that described in the specification to my application Serial No. 250,735. The accompanying drawing shows the apparatus so applied.

R is a closed reservoir charged with combustible liquid, having an opening at top fitted with a tubular plug, t', through which is screwed the rod t, whose lower end closes more or less the small opening leading into the pipe u with shut-off cock m. The lower end of the 65 pipe is bent upward and fixed in the nozzle a of the Bunsen burner, constructed as described in my said application.

At p an annular chamber is fixed on the pipe u, which communicates therewith by a small 70 hole regulated by a screw-plug, q, and which has several small jets at top, so that some of the combustible vapor will pass from u into p, and being ignited on issuing from the jets will heat the pipe, so as to convert the whole of the 75 descending liquid into vapor, which passes up into the burner, where it mixes with the air and is burned, as described in my said prior application. Below the chamber p is a cup, o, for the reception of a small quantity of inflammable liquid for heating the pipe on starting.

Having thus described the nature of my invention and the best means I know for carrying the same into practical effect, I declare that what I claim is—

1. An apparatus for heating the igniting-tube of a gas-motor engine, consisting of a closed receptacle charged with combustible liquid, a pipe leading downward therefrom to a Bunsen or similar burner, and means for heating 90 the pipe to volatilize the liquid before it issues into the said burner, a vertical internally-screw-threaded tube in the upper part of the receptacle containing the liquid, and a screw-rod adjustable in the tube to more or less close 95 the upper end of the pipe leading to the burner, substantially as described.

2. An apparatus for heating the igniting-tube of a gas-motor engine, consisting of a closed receptacle charged with combustible liquid, 100

a pipe leading downward therefrom to a Bunsen or similar burner, an internally-screw-threaded tube in the upper part of the said receptacle, a vertical screw-rod adjustable in 5 said tube to more or less close the upper end of the pipe leading to the burner, and a heater on the pipe to volatilize the liquid before it enters into the burner, composed of an annular chamber arranged around the pipe beneath 10 the burner and having jet-openings in its top and communicating by an opening with the interior of the pipe, and a screw-plug for con-

trolling said opening, substantially as shown and described.

In testimony whereof I have signed my name 15 to this specification, in the presence of two subscribing witnesses, this 26th day of January, A. D. 1888.

NICOLAUS AUGUST OTTO.
